UNITED STATES PATENT OFFICE.

JOHN H. PEGGS AND GEORGE M. OVERSHINER, OF ELWOOD, INDIANA.

IMPROVEMENT IN HOG-TRAPS.

Specification forming part of Letters Patent No. 147,346, dated February 10, 1874; application filed November 22, 1873.

To all whom it may concern:

Be it known that we, JOHN H. PEGGS and GEO. M. OVERSHINER, of Elwood, in the county of Madison and State of Indiana, have invented a new and useful Improvement in Hog-Trap, of which the following is a specification:

Figure 1 is a front view of our improved trap, part being broken away to show the construction. Fig. 2 is a side view of the same, part being broken away to show the construction.

Similar letters of reference indicate corresponding parts.

Our invention has for its object to furnish an improved device, simple in construction, convenient in use, and reliable in operation, for catching hogs and holding them securely while being ringed, marked, or castrated.

The invention will first be fully described, and then pointed out in the claims.

A are two sills, to which, near their forward ends, are attached two cross-bars, B. In a vertical longitudinal slot, in the middle part of the bars B, are pivoted the lower ends of the levers C, one of said pivots passing through a slot in the bars B, and having attached to its ends the ends of the loop or U-bar D, which drops into one or the other of a series of transverse notches formed in the upper side of the projecting end of the bars B. This enables the lower ends of the levers C to be readily adjusted at such a distance apart as the size of the hogs to be caught may require. The upper ends of the levers C are inserted in a vertical longitudinal slot in the top cross-bars E, the end parts of which are secured to the bars F, attached to or forming part of the boards or side frames G. To the outer side of each of the levers C is attached the end of a strap, H. The straps H of each pair of levers C pass over a small roller, I, pivoted in the slot of the cross-bar E, over a second roller, J, pivoted in the outer end of said slot, and to their projecting parts, or to chains H' attached to said parts, are attached weights K, sufficient to draw the upper ends of the levers C together, and hold the hog until the straps or chains H' can be passed over pins

L, attached to the ends of the bars B. I prefer to make the weights K in the form of buckets, baskets, or boxes, having stones or other heavy substances placed in them, so that the weight can be easily adjusted as required. The two pairs of levers C are placed at such a distance apart that when the one pair may clasp the neck of a hog the other pair may clasp him behind the fore legs. The weights K are supported, when the trap is set, by the arms M, attached to or formed upon the shaft N, and which enter holes in the straps H. The shaft N works in bearings attached to the upper part of the side frame F G, and to its middle part is attached, or upon it is formed, another arm, O, which rests upon the upper end of the bar P, so that the weights K may be supported by the bar P. The bar P is pivoted, at or near its center, to the side frame G. The space between the bars B is occupied by two boards, Q R, which are placed at a little lower level than the tops of the bars B. The rear board Q is stationary, its ends being secured to the sills A. The forward board R is pivoted, at the rear part of its end edges, to the sills A. One of the pivots S of the board R projects, and is bent upward along the side of the lower part of the bar P. T are pins attached to the rear edges of the side boards or frames G of the trap to receive the rails or boards of a fence, which is thus continued close up to the sides of the trap, so that the trap, when set, may seem to be a gap in the fence or pen with which it is connected.

In using the trap, the hog, in seeking to escape through a gap, steps upon the tilting board R, the tilting of which pitches him forward, so that his neck may be between the levers C. The tilting of the board R presses the arm S against the lower end of the pivoted bar P, which withdraws the upper end of said bar from beneath the arm O of the shaft N, allowing the weights K to drop, closing the levers C, which clasp the hog around his neck, and around his body in the rear of his fore legs, where he may be held securely by hooking the straps or chains H' upon the pins L.

Having thus described our invention, what we claim as new, and desire to secure by Letters Patent, is—

1. The combination, with the bar D, and lever C pivoted at one end thereof, of the horizontally and vertically slotted bar B, having a series of notches near one end, as described.

2. The combination, with weighted strap and chains H H', of shaft N, having arms M O,

pivoted bar P, and the pivoted board R, having an outer arm, S, on one of its pivots, as set forth.

JOHN H. PEGGS.
GEORGE M. OVERSHINER.
